UNITED STATES PATENT OFFICE.

GEORGE LEES, OF CHICAGO, ILLINOIS, ASSIGNOR TO HIMSELF, AND CHARLES C. HOVEY, OF BAINBRIDGE, NEW YORK.

SHEET-METAL CAN.

SPECIFICATION forming part of Letters Patent No. 665,020, dated January 1, 1901.

Application filed August 18, 1899. Renewed June 8, 1900. Serial No. 19,623. (No model.)

To all whom it may concern:

Be it known that I, GEORGE LEES, a citizen of the United States, residing at Chicago, in the county of Cook and State of Illinois, have 5 invented a new and useful Improvement in Sheet-Metal Cans, of which the following is a specification.

Various articles for food have heretofore been steam-cooked and put up in cans from 10 which the air has been exhausted, and the covers of the cans have been held in place solely by atmospheric pressure. With these cans it has been difficult to insure a tight seal and also to open the can when it was desired to remove the contents for use; and the 15 object of my present invention is to produce a can where the seal shall be as perfect as possible and where the cover can be removed with facility and without injuring the can.

In carrying out my invention the can-body 20 may be of any desired shape.

The upper edge of the can-body is turned over and bent downward and outward as a 25 flange into the segment of a circle, and the edge of the cover is also bent downward as a flange into the segment of a circle which coincides with the segment into which the flange of the body is bent, and between the said flanged segments I place a rubber gasket. 30 The cover is provided at about the center with a cupped portion perforated, to which I make a hemispherical cover and place a ball in the cup. When the air is exhausted by any suitable means from the can, the atmospheric pressure holds the cover down tightly 35 upon the rubber gasket, and the rubber gasket is seated in the segment-flange of the body, so that a tight joint is effected. The vacuum within the can holds the ball in the 40 cup of the cover firmly to its seat.

To open the can, it is only necessary to remove the hemispherical cover over the ball and with the finger roll the ball off its seat to admit the air into the can, so as to be able to 45 immediately and readily lift the cover from the body of the can.

In the drawings, Figures 1 and 2 represent elevations of forms of cans illustrating my invention, and Figs. 3 and 4 are vertical sections at the upper end of the cans shown in Figs. 1 and 2.

The can-bodies *a* may be of any desired shape. I have illustrated in Fig. 1 a tapering body and in Fig. 2 a body with parallel sides. The upper end of the body is turned 55 over and bent downward and outward into a flange *b*, which is the segment of a circle. This flange receives the gasket *c*, of rubber or other similar material. The cover *d* is preferably flat, and the outer edge is bent 60 downward into a flange *e*, which is a segment of a circle, which segment coincides with the conformation given to the flange *b* of the body, so that both flanges fit upon the gasket *c* and largely conform thereto. 65

The cover is cupped at *f* and centrally perforated, Fig. 3 showing a slightly-different form of cup to Fig. 4; but I do not limit myself to the form of cup. In this cupped portion of the cover I place the ball *h*, and I 70 employ a hemispherical cover *i*, fitting over the ball and passing down around and upon the edge of the cupped portion of the cover. This hemispherical cover may be screwed down to place or may simply fit snugly over 75 the cupped-up portion *f*, the object of the hemispherical cover being to prevent the accidental displacement of the ball *h*. When the air is exhausted from the can by any well-known or convenient method or apparatus, 80 the cover is held firmly down against the rubber gasket, and the said gasket is seated upon the segment-flange *b*, so as to effect an airtight closure of the can, and the vacuum in the can holds the ball *h* to its seat in the 85 cupped portion *f* of the cover, the same being protected by the hemispherical cover *i*. The cans are to be shipped in this form with the food products contained therein, and when it is desired to remove the contents of the 90 can this may be effected without in any way destroying the can-body or cover by simply removing or lifting off the hemispherical cover, which can be done with any screwdriver or similar instrument, and then rolling 95 the ball *h* off of its seat with the finger, so as to allow the air to enter the can through the perforation in the base of the cupped-up portion. The cover may then be at once removed intact to give access to the contents of 100 the can.

I do not limit myself to the use of the

cupped-up portion, the ball, and the hemispherical cover, because it is evident that any sharp-pointed instrument may be driven into the top of the can to make a minute opening through which air can enter, so that the cover may be removed.

I claim as my invention—

1. The combination with the body and cover of a sheet-metal can, of coinciding edge segmental bent flanges to said cover and body and a rubber gasket between the same, substantially as set forth.

2. A sheet-metal can comprising a body with the upper edge turned over downward and outward to form a segmental flange, a gasket of rubber or similar material seated upon the segmental flange, a cover having its edge turned downward as a segmental flange and coinciding with the segmental flange of the body and resting upon the gasket thereon substantially as set forth.

3. The combination with the body and cover of a sheet-metal can, of coinciding edge segmental bent flanges and a rubber gasket between the same, the cover of the can having

a cupped-up perforated portion and a ball resting in said cupped-up portion and an unattached removable protector above the said ball to prevent the accidental shifting of the same, substantially as set forth.

30

4. A sheet-metal can comprising a body with the upper edge turned over downward and outward to form a segmental flange, a gasket of rubber or similar material seated upon the segmental flange, a cover having its edge turned downward as a segmental flange and coinciding with the segmental flange of the body and resting upon the gasket thereon, a cupped-up or perforated portion formed in the cover, a ball seated in the cupped-up portion and a hemispherical unattached removable cover fitting upon the cupped-up portion and over the ball to protect the same, substantially as set forth.
